(57) **CLAIM**

The ornamental design for a carton, substantially as shown and described.

DESCRIPTION

FIG. 1 is a top perspective view of a carton according to the invention;

FIG. 2 is bottom perspective view of a carton according to the invention;

FIG. 3 is a front elevational view of a carton according to the invention;

FIG. 4 is a left side elevational view of a carton according to the invention, with the right side elevational view being a mirror image thereof;

FIG. 5 is a rear elevational view of a carton according to the invention;

FIG. 6 is top plan view of a carton according to the invention; and,

FIG. 7 is a bottom plan view of a carton according to the invention.

The broken lines in the figures illustrate unclaimed environment only and form no part of the claimed design.
